SIGHT GAUGE FOR OIL CONDUITS AND THE LIKE

John T. Krapp, Port Washington, N. Y.

Application February 23, 1956, Serial No. 40,290

Term of patent 14 years

(Cl. D52—1)

Fig. 1

Fig. 2

Figure 1 is a side elevational view of a sight gauge for oil conduits and the like showing my new design; and

Figure 2 is a top view thereof.

I claim:

The ornamental design for a sight gauge for oil conduits and the like, as shown.
